US0D1113714S

(12) **United States Design Patent** (10) **Patent No.:** **US D1,113,714 S**
(45) **Date of Patent:** ** *Feb. 17, 2026

(54) **POWER STATION**

(71) Applicants: **VIRIDI E-MOBILITY TECHNOLOGY (NINGBO) CO., LTD.**, Ningbo (CN); **ZHEJIANG ZEEKR INTELLIGENT TECHNOLOGY CO., LTD.**, Ningbo (CN); **ZHEJIANG GEELY HOLDING GROUP CO., LTD.**, Hangzhou (CN)

(72) Inventors: **Ye Yuan**, Zhejiang (CN); **Jia Li**, Zhejiang (CN); **Zequn Yu**, Zhejiang (CN); **Songlin Yang**, Zhejiang (CN); **Yue Ma**, Zhejiang (CN)

(*) Notice: This patent is subject to a terminal disclaimer.

(**) Term: **15 Years**

(21) Appl. No.: **35/518,669**

(22) Filed: **Aug. 22, 2023**

(80) **Hague Agreement Data**

Int. Filing Date: **Aug. 22, 2023**

Int. Reg. No.: **DM/232062**

Int. Reg. Date: **Aug. 22, 2023**

Int. Reg. Pub. Date: **Oct. 13, 2023**

(57) **CLAIM**

The ornamental design for a power station as shown and described.

DESCRIPTION

1.1: Perspective view 1, shown in an assembled state;
1.2: Perspective view 2;
1.3: Front view;
1.4: Back view;
1.5: Left view;
1.6: Right view;
1.7: Top view;
1.8: Bottom view;
1.9: Enlarged view 1, taken from detailed circle “1.9” in Reproduction 1.1;
1.10: Enlarged view 2, taken from detailed circle “1.10” in Reproduction 1.1;
1.11: Enlarged view 3, taken from detailed circle “1.11” in Reproduction 1.1;
1.12: Enlarged view 4, taken from detailed circle “1.12” in Reproduction 1.1; and
1.13: Perspective view 3, shown in a disassembled state. The dash-dash broken lines in the drawings depict the portions of the power station that form no part of the claimed design.

(Continued)

The dot-dash broken lines in the drawings depict the boundaries of the enlarged views and form no part of the claimed design.

The labels 1.9-1.12 in reproduction 1.1 form no part of the claimed design.

1 Claim, 13 Drawing Sheets
